WIRE FABRIC AND METHOD OF MAKING
THE SAMERaymond J. Guba, Philadelphia, Pa., assignor to
Audubon Wire Cloth Corporation, Philadelphia, Pa., a corporation of New Jersey

Application May 22, 1936, Serial No. 81,140

12 Claims. (Cl. 245—6)

My invention relates to wire belt fabric made up of helically coiled wires in interrelated arrangement disposed transversely of the belt fabric, and it comprises an improved type of belt fabric, and it comprises an improved type of belt fabric having sets of helically coiled wires of different twist—helically coiled wires of right-hand twist alternating with helically coiled wires of left-hand twist—with sets of cross connector wires in what may be termed independent association with the respective sets of helically coiled transversely disposed wires. The cross wire connectors are crimped, and the bends of such crimping are so spaced as to be in position for engagement by the oppositely disposed bights of the 15 helices of the respective helically coiled wires.

The ends of the helically coiled wires are positively connected with the ends of the crimped cross connector wires, as by knuckling, and those portions of the latter wires in engagement with 20 the bights of the helically coiled wires of one twist, float through the helices of the other helically coiled wires. The respective helically coiled wires of different twist are in slightly separated condition so that the helices of the same may 25 lie in the same plane longitudinally of the belt, and by preference the helices are of material length widthwise of the helically coiled wires and relatively flat. I am thus able to produce a belt 30 of extreme strength and flexibility; one that will track true in passing over drums or pulleys by reason of the presence of the alternating wires of different twist; one that will have no appreciable stretch longitudinally, and one that will not contract transversely.

My improved belt structure is, in effect, made up substantially of two fabrics—one fabric comprising helically coiled wires of right-hand twist in which the bights of the same are interengaged by one set of crimped cross connector wires, 35 and the other fabric comprising helically coiled wires of left-hand twist in which the bights of the same are interengaged by the other set of cross connector wires; the respective helically coiled wires of one fabric nesting within the 40 helically coiled wires of the other fabric.

The relation between the helically coiled wires and the cross connector wires is such that it may be said that the belt structure is made up of a plurality of sets of units; each unit comprising a 45 helically coiled wire and a crimped cross connector wire with their ends connected together; one group of such units including helically coiled wires of right-hand twist, and the other group including helically coiled wires of left-hand twist.

These and other features of my invention are

more fully set forth hereinafter; reference being had to the accompanying drawings, more or less diagrammatic in character, in which:

Figure 1 is a plan view, partly broken away, of a section of belt fabric within the scope of my 5 invention.

Fig. 2 is an edge view of the same.

Fig. 3 is a fragmentary sectional view taken on the line III—III, Fig. 1, and

Figs. 4 and 5 are fragmentary views illustrating unit groups of wires; each group comprising a helically coiled wire and a crimped cross connector wire positively connected therewith; Fig. 4 showing a helically coiled wire of right-hand twist, and Fig. 5 showing a helically coiled wire 15 of left-hand twist.

Helically coiled wires have long been employed in the manufacture of woven wire fabric and of belt structures available for and used in many industries. In the main, these belts have been 20 made of helically coiled wires having the same twist. Belts made up of similarly coiled wires in interconnected relation and extending throughout the entire length of the same have a tendency to creep laterally in passing around the 25 drums or pulleys over which they are stretched and one practice of avoiding this tendency to creep is to arrange sections of wires of different twist in alternate relation longitudinally of the belt. In other instances, it has been proposed to 30 alternate individual wires of different twist on opposite sides or faces of the belt; the wires of different twist being interwoven together through the fabric, and in other instances it has been proposed to arrange wires of different twist in 35 alternating relation and to connect the same by cross connector wires which engage the bights of a pair of the directly adjacent wires of different twist; the bights of one helically coiled wire lying to one side of each cross connector 40 wire, while the bights of the other helically coiled wire lie at the opposite side of the cross connector wire.

My improved structure differs from those heretofore developed in that the bights of the several 45 helically coiled wires are independently engaged by cross connector wires—that is to say—each helically coiled wire has a separate cross connector wire engaging the bights of the helices on opposite sides of the same, and one of these cross 50 connector wires is positively connected to the helically coiled wire with which it is associated; the next cross connector wire engaging the bights of the opposite side at the first mentioned helically coiled wire and being posi- 55

tively connected to the next adjacent helically coiled wire of the same twist, and so on throughout the full extent of the belt. These cross connector rods or wires serve also to reinforce and strengthen the belt fabric. In addition, there is nested in the helically coiled wires of one twist, helically coiled wires of opposite twist, and the helically coiled wires of this second group are associated with other cross connector wires in the same manner as the first group. In order that the helices of the respective helically coiled wires may be held in proper position transversely of the belt; thereby preventing any contraction thereof, the cross connector wires are crimped; the crimps being spaced so as to exactly engage the bights of the helices of the several helically coiled wires.

The coils of the wires are quite flat, and they are much wider from side to side of the helices than between the upper and lower surfaces of the belt.

In Fig. 1 of the drawings, I have illustrated a plurality of helically coiled wires of right-hand twist, indicated at 1, and a plurality of helically coiled wires of left-hand twist, indicated at 2, which latter wires are alternately arranged with respect to the wires 1 and have their helices nested between or within the helices of said latter wires.

30 The helices of the respective helically coiled wires, which are in diagonal positions alternately, present bights at opposite sides of the same; those of the wires 1 being indicated at 1^a and 1^b, and those of the wires 2 being indicated at 2^a and 2^b. These bights are engaged by cross connector wires 3 and 4 which may be said to be arranged in pairs; the wires 3 engaging the bights 1^a and 1^b of the helically coiled wires 1, and the wires 4 engaging the bights 2^a and 2^b of the helically coiled wires 2.

The end helices 1^c and 2^c of the respective wires 1 and 2 terminate in opposite directions, and such terminals are in positive engagement with the ends of the cross connector wires 3 and 4; the cross connector wires 3 being connected thereto as by knuckling their ends 3^a at the marginal edges of the belt structure to the ends 1^c of the helically coiled wires 1, while the cross connector wires 4 are connected thereto as by knuckling their ends 4^a at the marginal edges of the belt structure to the ends 2^c of the helically coiled wires 2.

Such arrangement, it will be observed, provides unit elements, each of which is made up of a helically coiled wire and a cross connector wire. These unit elements are illustrated in Figs. 4 and 5, independently of the fabric; Fig. 4, showing a helically coiled wire of right-hand twist connected to a cross connector wire 3—the latter being crimped—and Fig. 5, showing a helically coiled wire of left-hand twist connected to a crimped cross connector wire 4. In each instance, the bights of the helices engage the root portions of the crimps. These cross connector wires serve also to strengthen the fabric.

In the formation of the belt, the bights at one side of the helices of each helically coiled wire engage the crimps of the cross connector wire attached to the next adjacent wire of the same twist; a condition that is clearly observable upon inspecting Fig. 1. Each helically coiled wire is attached to a crimped cross connector wire which engages the helices at one side of said helically coiled wire, while the helices at the opposite side

of said helically coiled wire engage the crimped cross connector wire attached to the next helically coiled wire of the same twist. Each set of the helically coiled wires is similarly arranged.

By reason of this arrangement of the helically coiled wires and the cross connector wires, there is present in my improved belt structure what may be said to be two independent belts. The wires of different twist nest with one another and, at the same time, the bights of the respective helices pass each other and the cross connector wires associated with one set of helically coiled wires, float through the helices of the other helically coiled wires. In this manner the two belt structures are in assembled relation but without positive connections between the helically coiled wires of different twist.

It is to be understood that modifications may be made in the construction and arrangement of the several elements of my improved belt structure without departing from the spirit of my invention; all of which is deemed to be within the scope of the appended claims.

I claim:

1. A belt fabric made up of a plurality of sets of helically coiled wires of right and left twist; the wires of one twist alternating with wires of opposite twist throughout the entire extent of the fabric, and pairs of cross connector wires associated with each of said helically coiled wires; one wire of each pair of said cross connector wires being positively attached to a helically coiled wire.

2. A belt fabric made up of a plurality of sets of helically coiled wires of right and left twist in nested relation; the wires of one twist alternating with wires of opposite twist throughout the entire extent of the fabric, and pairs of cross connector wires independently associated with each of said helically coiled wires; one wire of each pair of said cross connector wires being attached at its ends to a helically coiled wire.

3. A belt fabric made up of a plurality of sets of helically coiled wires of right and left twist; the wires of one twist alternating with wires of opposite twist throughout the entire extent of the fabric, and cross connector wires of crimped formation attached to each of said helically coiled wires; each of said crimped cross connector wires engaging the bights of a pair of helically coiled wires of the same twist and holding them in spaced relation.

4. A belt fabric made up of a plurality of sets of helically coiled wires of right and left twist; the wires of one twist alternating with wires of opposite twist independently of each other throughout the entire extent of the fabric, and cross connector wires of crimped formation attached to each of said helically coiled wires; each of said crimped cross connector wires engaging the bights of a pair of helically coiled wires of the same twist and floating through the helices of the other helically coiled wires; said crimped cross connector wires holding the helically coiled wires in spaced relation transversely of the belt fabric.

5. A belt fabric made up of a plurality of sets of helically coiled wires of right and left twist in independent relation and extending transversely of said belt, and a plurality of sets of cross connector wires passing through the respective bights of said helically coiled wires; the relation of the cross connector wires with the helically coiled wires of one twist with an associated cross wire connector is independent of the helically coiled wires of the other twist and their cross wire connectors.

6. A belt fabric made up of a plurality of sets of helically coiled wires of right and left twist in independent relation and extending transversely of said belt, and a plurality of sets of cross connector wires passing through the respective bights of said helically coiled wires; each of said helically coiled wires having a cross connector wire attached thereto at its ends and the relation of the cross connector wires with the helically coiled wires being such that each helically coiled wire of one twist with an associated cross wire connector is independent of the helically coiled wires of the other twist and their cross wire connectors. 5

7. A belt fabric comprising a plurality of sets of helically coiled wires of right and left twist in independent relation and extending transversely of said belt, and a plurality of sets of crimped cross connector wires passing through the respective bights of said helically coiled wires; said crimped cross connector wires holding the helically coiled wires in spaced relation and the relation of the crimped cross connector wires with the helically coiled wires being such that each helically coiled wire of one twist with an associated cross wire connector is independent of the helically coiled wires of the other twist and their cross wire connectors. 10

8. A belt fabric comprising a plurality of sets of helically coiled wires of right and left twist in independent relation and extending transversely of said belt, and a plurality of sets of crimped cross connector wires passing through the respective bights of said helically coiled wires; the relation of the crimped cross connector wires with the helically coiled wires being such that each helically coiled wire of one twist with an associated cross wire connector is independent of the helically coiled wires of the other twist and their cross wire connectors, and said crimped cross connector wires engaging the bights of the helically coiled wires at their bends and holding the latter in spaced relation transversely of the belt. 15

9. The method of forming a belt fabric structure which consists in arranging helically coiled wires of opposite twists in nested relation; associating cross connector wires with said helically coiled wires in independent relation; a cross connector wire being attached to each of the helically coiled wires, and arranging the cross connector

wires attached to one of said helically coiled wires of each twist to float through the helices of the helically coiled wires of opposite twist. 20

10. The method of forming a belt fabric structure which consists in arranging helically coiled wires of opposite twists in nested relation; the wires of one twist having their helices extending beyond the helices of the wires of opposite twist longitudinally of the belt fabric; associating cross connector wires with each of said helically coiled wires in independent relation; a cross connector wire being attached to each of the helically coiled wires, and arranging the cross connector wires attached to said helically coiled wires of each twist to float through the helices of the helically coiled wires of opposite twist. 25

11. The method of forming a belt fabric structure which consists in arranging helically coiled wires of opposite twists in nested relation; associating cross connector wires of crimped formation with said helically coiled wires in independent relation; each of said crimped cross connector wires being attached to a helically coiled wire, and arranging the cross connector wires attached to each of said helically coiled wires of each twist 30 to float through the helices of the helically coiled wires of opposite twist; the crimped portions of said cross connector wires engaging the bights of the helically coiled wires and maintaining them in fixed position transversely of the belt fabric. 35

12. The method of forming a belt fabric structure which consists in arranging helically coiled wires of opposite twists in nested relation; the wires of one twist having their helices extending beyond the helices of the wires of opposite twist; associating cross connector wires of crimped formation with each of said helically coiled wires in independent relation; each of said crimped cross connector wires being attached to one of the helically coiled wires, and arranging the crimped cross connector wires attached to one of said helically coiled wires of each twist to float through the helices of the helically coiled wires of opposite twist; the crimped portions of said cross connector wires engaging the bights of the helically coiled wires and maintaining them in fixed position 40 transversely of the belt fabric. 45

RAYMOND J. GUBA.
